UNITED STATES PATENT OFFICE.

PAUL F. COX, OF CHICAGO, ILLINOIS.

ADDRESSING APPARATUS.

1,387,592.

Specification of Letters Patent. Patented Aug. 16, 1921.

Application filed May 21, 1920. Serial No. 383,240.

To all whom it may concern:

Be it known that I, PAUL F. Cox, a citizen of the United States, residing at Chicago, in the county of Cook and State of Illinois, have invented certain new and useful Improvements in Addressing Apparatus; and I hereby declare that the following is a full, clear, and exact description thereof, reference being had to the accompanying drawings, which form part of this specification.

This invention is a novel addressing apparatus and in particular is an improvement upon the form of apparatus shown in my Patent No. 1,344,384, dated June 22, 1920.

A primary object of the invention is to provide a novel addressing apparatus which can be attached to a web printing press and operated by and from the mechanism of the web printing press in unison therewith, and which is preferably located at or adjacent the former of the press and will apply successive addresses to successive newspaper impressions descending the former; and which mechanism will not be in the way, or interfere with the threading of the press or the control of the press by the pressman, permitting him to run the press regardless of the presence of the addressing attachment the same as if the addressing attachment was not present; and at the same time the addressing mechanism will be under the control of the addressing-operator regardless of the operation of the press itself (other than that if the press should be stopped the addressing mechanism would be stopped); and the addressing mechanism can be thrown into or out of effective operation at the will of the addressing operator without stopping, slowing down, or otherwise affecting the operation of the printing press proper.

Other particular objects of the invention are—

(1) To provide novel means for taking a slug from the galley and presenting it to the printing point and discharging same after the printing operation.

(2) To provide novel means whereby after the printing operation the printing slugs will be turned before or as they are discharged from the holder and be delivered therefrom type uppermost; so that the type will be protected from injury and the slugs will be received in the receiving galley in

the same order in which they are fed from the feed chute to the printing mechanism.

(3) To provide novel means for clamping the slugs endwise on the carrier while they are being carried thereby to and past the printing point.

(4) To provide novel means for also clamping the slugs facewise on the carrier while they are being carried thereby from the feed chute to and past the printing point.

(5) To provide novel means whereby an indicating mark or designation may be impressed upon the first or last paper of a series of papers going to the same town, so that the delivery tender can readily separate the different groups of papers according to their intended destination.

(6) To provide novel means whereby each time such an indicating mark is impressed upon the paper, for the purpose stated, a signal will be given to the press attendant who is removing the papers discharged from the folder.

(7) To provide novel means whereby slugs may be readily discharged from a slug holding galley into the feed chute.

(8) To provide novel means for removing an empty galley out of the way of a full galley.

(9) To provide novel means whereby each time a galley is placed into position for discharging slugs into the feed chute the inking mechanism will be supplied with a sufficient amount of ink to ink the slugs supplied by said galley.

(10) To provide novel means whereby ink is supplied from the fountain when slugs are supplied to the feed chute.

(11) To provide novel means whereby the ink ductor roller is shifted only when a slug galley is placed in position preparatory to discharging slugs into the feed chute, and when such galley is removed the ductor roller becomes and remains operative as a distributing roller.

(12) To provide novel means for discharging the slugs into the receiving galley.

(13) To provide novel means whereby the addressing operator can at will stop the feeding of the slugs without stopping the operation of the various mechanisms and without necessitating the stoppage of the printing press; and whereby the addressing operator can at will resume the effective

addressing operations regardless of any interval of time which may have elapsed between the cessation and resumption of the addressing operations.

5 (14) To provide novel indicating means whereby when the addressing mechanism is put out of effective operation the packer-box tender is notified, preferably by a visual signal, so that he will be advised by such 10 signal both when the addressed papers are being delivered from the folder, or when non-addressed papers are being delivered.

(15) To provide novel means whereby in 15 case of clogging or jamming in the addressing mechanism the latter will be put out of effective operation before any injury can result.

(16) To provide signal devices whereby 20 if the addressing mechanism should be rendered ineffective by clogging or jamming of the parts the operator will be notified.

As stated the invention is particularly 25 adapted for use in connection with printing presses and other mechanisms handling articles so that when the articles are delivered they are also addressed and ready for mailing.

When the novel mechanism is attached to 30 an ordinary printing press or newspaper press the web handling mechanism of the press serves as the feeding and delivery mechanism for the addressing attachment and the power mechanism of the press serves as the actuating means for the addressing 35 mechanism. The addressing mechanism is compact and economical, and can be readily adapted for and applied to any of the standard makes of web printing machines.

I do not however consider the invention 40 in its broader aspects restricted to use with printing presses or other machines; nor to the specific construction shown; but will explain the same with reference to the accompanying drawings which illustrate one 45 practical embodiment and application of the invention and will enable others skilled in the art to readily adapt and use the invention. The essentials of the invention and novel combinations of parts and novel features of construction, for all of which protection is desired, are set forth in the claims.

In said drawings:

Figure 1 is a side elevation of the novel 55 addressing mechanism as applied to the folder former end of a web printing machine; parts of such former and machine being indicated in section.

Fig. 2 is a part plan and part horizontal section on the line 2—2, Fig. 1.

60 Fig. 3 is a vertical section on the line 3—3, Fig. 2.

Fig. 4 is a view, partly in section, looking inwardly and downwardly from the position indicated by the arrow marked 4 in Fig. 3.

Fig. 5 is a detail section on the line 5—5, 65 Fig. 2.

Fig. 6 is a detail section on the line 6—6, 70 Fig. 2.

Fig. 7 is a detail section on the line 7—7, 75 Fig. 5.

Fig. 8 is a detail view of the devices for holding the drive gear declutched.

Fig. 9 is an enlarged top plan view of the inking mechanism.

Fig. 10 is an enlarged side view of the 75 inking mechanism.

Fig. 11 is a detail sectional view of Fig. 8.

Fig. 12 is a detail sectional view showing the turning of a slug.

Fig. 13 is a detail view of the slug holding devices.

Fig. 14 is a detail section on the line 14—14, Fig. 1.

Fig. 15 is a detail view of the slug feed stop devices.

Fig. 16 is a detail face view of part of the galley support connected with the feed chute.

The operative parts of the addressing mechanism are mounted in a suitable frame, 90 the particular form of which is not material, provided it affords proper support and bearings for the operative parts of the addressing mechanism.

In the present instance the addressing 95 mechanism is shown as designed to use individual printing members of any suitable kind, shown as slugs or type metal bars A each bearing the name and address of the addressee or other desired indicia. These 100 slugs are supplied from a feed chute 2, which is preferably supported upon the frame 1 in vertical position and can be supplied with the slugs from loading galley G such as are commonly used in the so-called 105 addressing machines now on the market. The feed chute may be supplied with these slugs and replenished therewith without stopping the operation of the machine until all the addresses have been printed.

The lower end of the chute 2 is supported 110 upon a base plate 2^a in which is slidably mounted an ejector slide 3, that operates through suitable slots in the front and rear walls of the chute and is adapted to successively eject the slugs from the chute one at a time in the usual manner. In the construction shown the slugs are ejected base first, type outermost, from the chute 2, and to prevent injury to the type the end of the 120 ejector may be recessed as shown in Fig. 2, so that it will not injure the type surfaces.

The slide may be operated by any suitable means. As shown it is reciprocated by means of a crank rod 3^a (Figs. 1 and 2) 125 pivotally connected with the slide and with a crank pin 3^b attached to a rotatable slug carrier 4, keyed on a shaft 4^b, journaled in

suitable bearings in the frame 1, and rotated as hereinafter explained.

The slug is ejected from the chute 2 onto spaced fingers 2^c attached to or formed on the inner end of the plate 2^a and is supported by such fingers in position to be taken by radially projecting fingers 4^c formed integral with, or attached to, the carrier 4; the fingers 4^c passing between the fingers 2^c and picking up the slug lying thereon as the carrier 4 rotates with the shaft 4^b.

The slug taken by the fingers 4^c may be securely held on the carrier 4 by any suitable devices. As shown (Figs. 1 and 2) a gripper 5 is provided having a head 5^a adapted to engage the adjacent end of the slug and press it tightly against a plate 4^f attached to the side of the carrier adjacent the supporting frame (see Figs. 2, 4 and 13). This gripper is shown as pivoted on a pin 4^e on the end of the shaft 4^b, and the gripper is slotted to accommodate the crank pin 3^b. The gripper may be normally held in closed position by means of a spring 5^c interposed between the end 5^b of the gripper, (opposite its head 5^a), and carrier 4, as shown.

The gripper is opened and closed at the proper times in its rotary movement by suitable means. As shown a cam 15^a is attached to a shaft 15 (journaled in and extending through the carrier 4 adjacent the fingers 4^c) and cam 15^a is adapted to engage the adjacent end of the gripper at the proper time to cause it to release the slug at the proper point; and the cam will release the gripper at the proper time to enable it to clamp another slug just after such slug has been fully ejected from the chute by the slide. Preferably the gripper 5 is provided with an adjustable cam engaging member 15^x adjustably secured to the gripper (see Figs. 1, 2 and 4) so that the extent of opening movement of the gripper can be nicely regulated.

The cam 15^a is so disposed and of such length that the gripper will be opened before the fingers 4^c reach the fingers 2^c, and will close immediately after the fingers 4^c begin to take the slug away from the fingers 2^c, and will hold the slug firmly while the slug is being inked and while it is making an impression; then the gripper will be opened so as to release the slug, and may remain open until another slug is taken from the fingers 2^c.

In the construction shown the gripper is adapted to close upon and clamp the slug endwise just after the latter is ejected from the chute and while it is held in ejected position by the slide the end of the slide preventing any jarring or jamming of the slug out of position as the gripper closes thereupon.

These slugs, if desired, may be inked before being introduced into the chute so that

they will not require any inking in the machine; or they may be inked by any suitable means after they are taken from the galley by the carrier 4^c and before reaching the printing point. An inking roll 6 is provided, which roll may be a self-inking roll of any well known type; but preferably receives ink from a fountain roll 6^b (see Figs. 1, 9 and 10) as hereinafter described.

I also preferably provide means for clamping the slug A laterally against the fingers 4^c to prevent the slug tilting while it is being carried by the carrier past the inking roll and past the printing point. For this purpose I provide a clamping finger 15^e which is pivoted within a centrally disposed transverse slot within the carrier 4 (see Figs. 2 and 6), said finger being pivoted on a pin 15^d at one side of the shaft 15 and curving around said shaft, and being of such length that in one position its end will project beyond the periphery of the carrier 4 and engage slug A and clamp it against the fingers 4^c, as indicated in Fig. 6. The finger 15^e is normally projected by means of a suitable spring. As shown in spring 15^f engages the inner end of the clamp 15^e. The opening and closing of the finger is controlled by suitable means. As shown the finger 15^e has a projection 15^e which engages a cam 15^w attached to the shaft 15, and said cam is so located and formed that at the proper point during the rotation of the carrier (and the shaft 15) the clamp finger is permitted to suddenly project and clamp the slug against the fingers 4^c just as the slug is removed from the fingers 2^c by the fingers 4^c; and the gripper 5 clamps the slug. The clamp finger 15^e is disengaged from the slug and retracted within the slot in the carrier just after the printing operation (see Fig. 3). The gripper and the clamp finger effectively prevent the slugs becoming displaced radially by centrifugal force or otherwise on the carrier while they are being carried thereby.

The shaft 15 is rotated once for and during each rotation of the carrier by any suitable means so as to operate the several cams and devices connected therewith in the proper time. As shown the shaft 15 has a pinion 15^x (see Figs. 2 and 5) on one end meshing with a fixed gear 15^h attached to the frame circumferentially of the shaft 4^b so that the pinion 15^x travels orbitally around gear 15^h as the carrier rotates and causes the shaft 15 to rotate once for each rotation of the carrier.

After being inked the slug is carried on by the carrier to the point of impression. After the impression is made the gripper 5^a and the clamp finger 15^e are caused to release the slug by the action of the cams on the shaft 15, and both the gripper and the clamp finger are held open until another

slug is taken by the carrier from the fingers 2^c.

As soon as the gripper releases the slug the latter would naturally be discharged by gravity, aided by centrifugal force, into a slug funnel or guide 8 (Figs. 3 and 12) by which it is directed into a receiving chute 8^a, from which chute the slugs can be directed into removable galleys which can be attached to the outer end of the receiving chute in the usual manner, as in ordinary type setting machines and addressing machines using slugs.

Any suitable means may be provided for positively discharging the slug from the carrier after printing. I have provided curved stripping fingers 8^g, as indicated in Figs. 1, 3 and 12, which project into annular grooves 4^k in the periphery of the carrier 4, and between the fingers 4^c, so that as the carrier rotates the fingers 8^g will cause the slugs to slide radially off the fingers 4^c into the receiving galley or chute, as herein-after described.

25 *Slug turning devices.*

To deliver the slugs into the galley face uppermost I provide novel means for reversing or turning the slugs between the printing point and the galley. As shown a finger 15ⁱ (Figs. 2, 3, 4 and 6) is attached to the shaft 15 within a slot in the carrier and so located therein that said finger will come into contact with the slug just after the printing operation (see Fig. 3) and will tend to turn the slug over after it is released by the clamp finger and while the slug is still clamped endwise between the gripper 5 and the plate 4^f. (See Figs. 12 and 13.)

40 If desired the said gripper and plate might be provided on their inner faces with little bearing points 5^x and 4^x as indicated in Fig. 13 upon which the slug will easily turn and the finger 15ⁱ will turn the slug over, as indicated in Figs. 3 and 12, so that the slug will enter the chute feet foremost as shown in Fig. 12 and the slug will be discharged from the chute into the galley type face uppermost.

50 The addressing apparatus is especially designed and adapted for use in connection with printing presses and to address newspapers, or other printed articles as they are printed on the machine; and therefore in the example shown the frame 1 is so constructed that it can be readily attached to part of the printing press; and preferably in such position that the carrier will cause the slugs to print the web or sheets descending the folder former of such machine. In the drawings I have illustrated part of a web printing newspaper press to which the invention is applied; which press may be a rotary, flat bed, or other type of press.

F designates the folder former of the 65 printing press; R the usual roller mounted on a shaft S at the top of the former and rotated as usual to assist the web of paper W to and over the former. The shaft S is driven by gearing (not shown), and above 70 the shaft S is a tie rod T, which usually carries spring pressed rollers (not shown) to hold the web W in contact with the roller R at the top of the former. Below the shaft S is a bar or rod B which supports the upper 75 end of the former F. All of these parts are of ordinary construction and arrangement and are well known, and will be readily understood, and more fully described and shown in my Patent No. 1,344,384, dated 80 June 22, 1920.

The carrier 4 is thus mounted, adjacent the former in such position that during the rotation of the carrier the slug will be inked and then brought into contact with and 85 print the address upon the paper W passing down the former F preferably in the margins between successive impressions.

90 The shaft 4^b is rotated, as hereinafter described, at such speed that the speed of movement of the face of the addressing slug carried by carrier 4 equals the speed of travel of the paper over the former, and the impression is therefore made on the moving web by the moving slug. To prevent 95 injury to the slug or to the web during the impression I preferably cut a small opening in the former F at the point of impression and mount an impression roller 7 at this point beneath the face of the former, so that 100 the impression will be actually made upon the paper while it is traveling by a traveling slug; this impression roller may be rotated by friction.

105 The shaft 4^b may be driven by any suitable means when the invention is embodied in a separate addressing machine or by any suitable driving connection with some driven part of the machine to which the addressing mechanism is attached. When applied to a printing mechanism the parts should be so driven and the gearing so proportioned that the slugs A on the carrier will be moving at the printing point at the same speed as the paper or article to be impressed passing 115 such point.

120 In the example shown, the shaft 4^b carries a gear 4^m which meshes with a gear 4° attached to and driven by the shaft S; and the gears 4^a and 4° are so proportioned that the slug carrier will be rotated once for each newspaper or impression on the paper, when applied to a printing press, and the parts adjusted so that the different addresses will be successively printed upon the paper, preferably in the margins between successive impressions thereon, so that each newspaper as it passes over the former has the address 125

of the individual for whom it is intended printed upon it before it reaches the folder rolls.

5 *Group designating mechanism.*

When the invention is utilized for addressing newspapers or other mail matter in quantities it is desirable that the various groups of papers going to a number of 10 parties in the same town can be easily distinguished and separated by the attendant. For this purpose I provide novel means whereby a distinctive mark may be placed upon the first or the last of a series of 15 papers or objects addressed to go to a certain place, and whereby when the addresses change from one series to another, a mark is applied to the last paper of the series, or to the first paper of the next succeeding 20 series.

A marker 14 (Figs. 3 and 5) is connected with the carrier but is normally retracted out of operative printing position, but at the proper time is projected so that it will 25 also print a mark on the paper beside the impression made by a slug upon the paper.

As shown (Figs. 1, 3, 4, 5, and 6) the marker 14 is carried by a curved flat spring 14^a attached to a block 14^b secured to the side 30 of and projecting radially from the carrier 4. The spring 14^a normally holds the marker 14 in such position that its printing surface does not project beyond the periphery of the type face of the slug carried by 35 the carrier 4. The marker 14 normally lies beside the fingers 4^c, but out of position to contact with the web of paper being printed by the slug. The marker 14 is projected into printing position at the proper time by suitable means preferably controlled by cam plates which are fed in through the feed chute with the slugs.

The spring 14^a has a cam end 14^c which is adapted to engage a trip-pin 14^e mounted in 45 the frame (Figs. 2, 3, 4, 5) which pin is projected into the path of the cam end 14^c of spring 14^a when it is desired to have the marker operated. When this pin 14^e is projected (see Fig. 5) the end 14^c of spring 14^a 50 rides thereon and the marker 14 is projected sufficiently to cause its printing surface to contact with the web of paper and print an indicating mark, such as "Town," thereon beside the address simultaneously printed 55 thereon by the particular slug that is then being carried past the printing point. The marker may be inked in any suitable manner. As shown when it is projected it receives ink from an inking device of any 60 suitable construction mounted upon the frame in the path of the marker to supply ink thereto before it reaches the printing point. I preferably use a fountain or self-inking roller 14ⁿ to supply ink to the marker.

As soon as the marker has operated the 65 trip pin 14^e is retracted until it is again projected by a cam plate as hereinafter explained.

The trip pin 14^e may be conveniently and certainly retracted by providing the block 70 14^b with a cam surface 14^f (Figs. 5 and 7) which engages the projecting end of the pin and moves it out of the path of spring 14^a immediately after the marker has operated.

In the construction shown the projection 75 of the pin 14^e is controlled by the following means:

A cam-plate 11, preferably of brass is placed between the last address slug of one town series and the first address slug of 80 another town series, and this cam plate is fed into the feed chute together with the address slugs. These cam plates are thinner than the slugs; and the discharge opening of the feed chute 2 can be made large enough 85 to permit the simultaneous passage, when necessary, of a slug and a cam plate, but will prevent the simultaneous passage of two address slugs. The cam plates will pass through the machine just as the slugs do and 90 can be carried therethrough simultaneously with a slug the cam plate being clamped and held on the carrier together with a slug by gripper 5 and clamp finger 15^e.

When a slug and cam plate are simultaneously ejected from the feed chute the cam plate engages and raises a roller 11^a on a finger 11^b attached to a lever 11^c (Figs. 1, 2 and 3) pivoted on the frame beside the chute: said finger 11^b projecting in rear of 95 the feed chute so that the roller lies adjacent the outlet slot in the feed chute and above the fingers 2^c, and in such position that while the roller would not be affected by the passage of a slug, it will be engaged and raised 100 if a slug and cam plate are simultaneously ejected. When roller 11^a is raised it oscillates the lever 11^c and depresses its forward 105 end.

The forward end of the lever 11^c overlies 110 a dog 12 pivotally mounted on the upper end of a lever 13 pivoted on the frame adjacent the slide 2, said lever 13 depending below said slide. Dog 12 has a pin 12^a on one side, and when the dog is depressed by the lever 11^c 115 the pin 12^a is lowered into position to engage a catch 2^e on the slide 2 (Fig. 3). When the slide moves forward if dog 12 is lowered catch 2^e engages the pin 12^a and moves the dog and the upper end of lever 13 120 inward with the slide.

The lower end of lever 13 is connected by a link rod 13^a to one arm 13^b of a bell crank lever pivoted on the frame (see Figs. 2 and 4) and the other arm 13^c of this lever is 125 pivotally connected to the trip pin 14^e, so that when the dog 12 is moved inward by the slide the trip finger 14^c is projected in a

position to engage a member 14^e. When the slide moves backward catch 2^e releases the dog 12 and the latter is immediately thrown upward by a spring 12^f attached to the frame so as not to be again engaged by the catch until the dog is again depressed by the ejection of a cam plate from the feed chute. The dog and lever 12 are returned to normal position by reason of their connection with the trip pin 14^e when the latter is retracted by the action of the cam 14^g.

Signal for passage of town slugs.

The dog 12 has a pin or finger 12^e (Figs. 2 and 3) which overlies a spring 12^f attached to the frame and which spring is adapted to normally hold the dog elevated so that this finger 12^e will not engage the catch 2^e. When the dog is depressed by the action of the lever 11^e the spring 12^f is depressed and its free end engages a circuit closing device 12^g (Fig. 1) which is electrically connected in a circuit including a conductor 12^b, a visual or audible signal 12^c (a light being shown) a battery or other suitable electrical source 13^p, and conductor 13^g back through the metal of the machine, as indicated in Fig. 1. When the contact 12^f is closed a light or signal will be given to the packer box tender and he will know that another town or division of papers is coming to him and be ready to separate them when they come. Thus a signal will be given the operator for each town passing through.

Means for throwing the addressing mechanism into and out of operation.

It is desirable to have the addressing mechanism entirely under the control of the address operator regardless of the control of the printing press by the printing press operator, so that the address operator can throw his addressing mechanism into and out of operation at will without having to interfere with the operation of the printing press while the operator may be making ready the addressing mechanism, or adjusting the same.

For this purpose suitable means are provided whereby the addressing operator can throw the addressing mechanism into or out of operation without disconnecting it from the press and preferably when the addressing mechanism is thrown out of operation the carrier is permitted to continue its rotation but ineffectively.

In the construction shown the pitman 3^a (Figs. 1, 2, 15) is provided with a notch 3^e near one end which notch is normally engaged with a pin 3^f on the slide 2 and when so engaged causes the slide to reciprocate as above described. The pitman has a depending finger 3^g at the outer side of the notch,

and at the inner side of the slot has an elongated straight-bearing portion 3^h for a purpose hereinafter referred to:—Above the notch the pitman has an upwardly projecting lug 3ⁱ carrying a pin 3^j.

Pivoted on a pin on the side of the feed chute adjacent the pitman 3^a, is a cam lever 23 having a cam 23^b, by which it can be manipulated. This lever may be frictionally held in either position by any suitable well known means and the movement of the lever may be limited by pins 23^d and 23^e attached to the chute 2 at opposite sides of arm 23^b, as shown.

When the machine is normally operating the arm 23^b is set against the stop pin 23^e, in which position the cam lever 23 is above and out of the path of the pin 3^j (see Fig. 1). If the operator desires to stop the feed of the slugs and thus stop the effective operation of the addressing apparatus he can throw the arm 23^b against the pin 23^d which will lower the cam lever 23 into position to be engaged by the pin 3^j and as the slide starts inward under the action of the pitman 3^a the pin 3^j rides up on the cam lever 23 and raises the end of the pitman 3^a until the pin 3^f is clear of the inner side of the notch 3^e (Fig. 15) and then on the outward movement of the pitman the part 3^h of the pitman simply rides upon the pin 3^f leaving the slide 2^a in its innermost position. The slide 2^a remains in this position until the cam lever 23 is returned to normal position (Fig. 1) permitting the pitman to drop and again engage notch 3^e with the pin 3^f.

By shifting lever 23 the addressing operator can at any time start or stop the operation of the addressing apparatus independently of the operation of the press which does not have to be stopped in order to stop the addressing operation.

Signaling stoppage of addressing operation.

To notify the packer box tender when the addressing operation is stopped I provide a suitable signaling apparatus. In the example shown an electrical contact 23^m (Fig. 1) is attached to the machine adjacent the handle 23ⁿ of the cam lever 23. This contact is connected by a wire 13ⁿ with a suitable signal, such as a light 13°, located where it will be most readily heard or seen by the packer box tender; this signal is connected in circuit with a suitable battery or source of electricity 13^p, grounded to the metal of the machine by a wire 13^g.

When the cam lever 23 is thrown into position to cause pitman 3^a to disengage the slide 2^a, as described, the contact is operated to close the electrical circuit through the signal, battery and frame of the machine; and the signal remains on until the operator returns the lever 23 to position to

permit the addressing mechanism to again begin effective operation.

Receiving galley and packer.

5 At the receiving end of the chute or galley is a curved plate 8^a (Figs. 1 and 3) which is adapted to direct the slugs into the galley. Above this plate and at the lower end of the stripping fingers 8^c is a preferably hinged plate 18 against which the slugs contact as they are directed by the stripping fingers 8^c and the curved plate 8^a into the galley. This hinged plate 18 may be yieldingly held in normal position by means of 15 any suitably arranged spring.

If for any reason an address slug should be improperly positioned as it passes between plates 8^a and 18 plate 18 will yield and prevent the slug being injured as it is moved 20 forward into the galley.

The slugs are moved forward in the receiving galley by means of rotary cam packers 18^b mounted on a shaft 18^c suitably journaled in the frame, the said shaft being operated by a train of gears 8^e from a gear 4^w 25 on the shaft 4^b. To prevent the slugs falling backward against the packing cams I preferably provide a safety catch device (see Fig. 14) which is shown as a beveled 30 pin 18^m projecting through the side of the galley and yieldingly pressed inward into the path of the slugs by a spring 18ⁿ, and this pin yields as the slug moves therewith, and then moves into position to prevent the 35 slug toppling over.

Safety clutch.

In order to prevent possible injury to the addressing mechanism in event of clogging 40 or binding of any of the parts thereof during its operation, I preferably yieldingly connect the driving gear 4ⁿ with the shaft 4^b. In the example shown (Figs. 2, 4 and 8) the gear 4ⁿ is loosely mounted on the 45 shaft 4^b; and on the outer end of the shaft besides the gear is splined a sleeve 40 provided with a grooved collar 41 at its inner end and with a clutch face or tooth 42 on its inner end adapted to engage a corresponding recess or clutch face in the opposed end of the hub of gear 4ⁿ. The sleeve is normally pressed inward by means of a spring 43 interposed between the collar 41 on the sleeve and a collar 4^r fastened on the 55 end of the shaft 4^b. The sleeve 40 is permitted sufficient play on the shaft 4 to engage or disengage the tooth or clutch surfaces 42 therefrom, and gear 4ⁿ is normally locked to the shaft 4^b by the sleeve 40.

60 In event of clogging or binding of the mechanism of the addressing apparatus, the spring 43 will yield or permit the clutch surfaces to disengage, and the gear 4ⁿ to turn on the shaft 4^b, thus preventing serious

damage. I prefer to provide means for locking the sleeve 40 to hold the clutch disengaged until the clogging or difficulty in the apparatus is remedied. As shown a bell crank lever is pivoted on the frame beside the shaft 4^b, said lever having an arm 44 engaging the collar 41, and having a latch arm 45 adapted to be engaged by a catch lever 46 pivoted on the machine adjacent the arm 45, and normally yieldingly pressed thereagainst by a suitable spring 47. When the sleeve 40 is faced outward to disengage gear 4ⁿ lever 44 depresses the arm 45 until catch 46 engages therewith and locks arm 45 as indicated in dotted lines in Fig. 8, preventing the sleeve 40 reengaging gear 4ⁿ until arm 45 is released from catch 46 by manually depressing the catch.

I preferably provide a double signal to notify the operator that the gear 4ⁿ is disengaged and the addressing apparatus has ceased operating. For this purpose I provide an electrical contact 48 connected with a suitable alarm, such as a bell 50, and a battery 49, the circuit being closed through the metal of the machine; so that when the 90 lever 44 is moved outward by the sleeve 40 it closes the contact 48 and causes the sounding of the alarm.

Inking mechanism.

In the preferred form of mechanism (Figs. 1, 4, 9 and 10) the inking roll 6 is provided with a coacting distributing roller 6^a and a distributing drum 6^s, which drum is mounted on a shaft 6^t carrying a pinion 100 6^u meshing with the driving gear 4ⁿ (see Fig. 4). Ink is supplied from a fountain 16, by means of a combination ductor and distributing roller 16^a, which is adapted to transfer ink from the fountain roller 6^b to 105 the distributing roller 6^a.

It is desirable in this class of machines where the slugs are fed from galleys to the feed chute that only the proper quantity of ink should be supplied from the fountain 110 for each galley of slugs fed into the machine, and for this purpose I provide means for automatically operating the ductor roller once each time that a galley of slugs is placed in the machine, so that only the 115 proper quantity of ink will be supplied from the fountain; after the ductor has taken ink from the fountain it can remain in contact with the distributing roller and acts as a distributing roller until another 120 galley is placed on the machine.

As shown one of the ductor supports 16^b is provided with an arm 16^c (Fig. 10) which in turn is connected by a link 16^d with an arm 16^e on a rock shaft 16^f mounted in suitable bearings on a loading galley support 20 attached to the upper end of the feed chute 2. The shaft 16^f carries an arm 16^g

to which is attached a rod 16^a that lies normally in the way of the galley to be placed upon the loading galley support 20. The link 16^a carries a pawl 16^c which engages a 5 ratchet 16^b on the shaft of the fountain roller 6^b so that each time the link is vibrated, or the ductor oscillated, the fountain roll will be shifted. When a loaded galley G is placed upon this support 20 (see Figs. 9 10 and 11) it will push the rod 16^a backward out of the way thereby rocking shaft 16^c and through the connections moving the ductor into contact with the fountain roller (as shown in full lines, Fig. 10) and when the 15 galley is moved out of the way the ductor moves back and becomes a distributing roller (as indicated in dotted lines in Fig. 10.)

Thus each time a loaded galley G is placed in position to discharge the slugs into 20 the feed chute the vibrator 16^a is moved into contact with the fountain roll (Fig. 10) and as soon as the galley G is moved out of the way the ductor drops back and becomes a distributing roll (dotted lines, Fig. 10) and 25 the ductor is thus semi-automatically operated by the mere placing of the loaded galley G on the support 20; and the ductor requires no attention on the part of the operator, and a proper supply of ink for inking 30 the slugs supplied by each galley is transferred to the inking mechanism; and an over supply of ink is prevented, as ink is taken from the fountain roll only when a galley of slugs is supplied to the feed 35 chute.

The slug loader.

The apparatus has a slug loading galley support 20 attached to the top of the feed 40 chute 2 upon which the loaded galleys are successively placed as indicated in Figs. 9, 10 and 11.

A loaded galley G is placed on this support at one side of the feed chute (see Figs. 45 9 and 11) (and thereby the ductor is actuated as described) and is then moved sideways along the support into position over the feed chute (as shown in dotted lines in Fig. 11) so as to discharge the slugs therefrom directly into the feed chute. In order 50 to prevent the slugs immediately dropping from the lower end of the galley into the chute as they are moved into position thereon, a retaining slide 21 is provided in the 55 lower edge of the galley support 20 (Figs. 9, 11) which can be operated by a finger piece 22; and after a loaded galley is placed in position on the support 20 (Fig. 11) slide 21 is moved inward so that it closes the upper 60 end of the feed chute (as indicated in dotted lines in Fig. 11) and then the galley is slid by hand sideways over the feed chute; then the operator retracts the slide 21 and permits the slugs to simultaneously descend

from the galley into the feed chute; and leaves the empty galley in this position over the chute. Then another loaded galley may be placed in position on the galley support (as indicated in dotted lines in Fig. 11) and the described loading operation repeated. 70 As the loaded galley is pushed inward it pushes the unloaded galley farther along sideways out of the way and such empty galley (pushed off by the loaded galley) is directed sideways into a chute 123 which it 75 descends by gravity and by which it is directed into position where the operator can conveniently take such empty galley and place it in position to receive the slugs discharged from the machine; and when a galley has been filled with the used slugs and is removed from the discharge chute, the operator has an empty galley conveniently at hand to put in its place.

When such an addressing attachment is 85 applied to a printing press the papers can be delivered therefrom addressed to different parties or destinations, ready for mailing; and the necessity for subsequently addressing such papers, or passing such papers 90 through an addressing machine is avoided; as well as the loss of time required for such operations; and the expense entailed in operating a separate addressing machine is 95 eliminated. The addresses are preferably applied to a margin of that page of the newspaper which will be outermost when folded. Customarily the press is so threaded that the outermost page is on the outside 100 layer of paper passing over the former so that no rearrangement of the forms in the press would be ordinarily necessary in order to use the attachment therewith.

The addressing attachment being located at the delivery end of the press can be readily adjusted to correctly print upon the margins whenever the papers are being properly delivered to the folding rolls; is not in the way when it is necessary to thread 105 the press or folder, in making ready the 110 press, or in case of rupture of the web.

While I have described the invention as embodied in an attachment for web printing presses and applied to such presses it will be obvious to those skilled in the art 115 that the invention could be readily embodied in a separate machine for addressing letters, envelopes, packages, and the like. In such case the frame would be properly modified and means provided for rotating the shaft 120 4^b manually or by power, all of which will be readily understood and provided by those familiar with the art.

What I claim is:

1. In a machine of the character specified; the combination of a feed chute, means for ejecting slugs therefrom, a rotary carrier adjacent the feed chute adapted to

- take an ejected slug and carry same past the printing point; a clamp on the carrier adapted to clamp said slug flatwise; with a rotatable cam mounted on the carrier, 5 and means for rotating the cam on its axis as it is carried around by the carrier to permit the said clamp to engage the slug when it is taken by the carrier and to cause it to release the slug after the printing operation.
- 10 2. In mechanism as set forth in claim 1, gripper means on the carrier adapted to clamp the slug endwise as it is taken by the carrier, and means for causing said gripper to release the slug after the printing operation.
- 15 3. In a machine of the character specified; the combination of a feed chute, means for ejecting the slugs therefrom, a rotary carrier adjacent the feed chute provided with 20 radially projecting fingers adapted to take an ejected slug and carry same past the printing point; a spring pressed clamping finger pivoted on the carrier and adapted to clamp said slug facewise on the fingers, and 25 a rotatable cam mounted on the carrier adjacent the finger and adapted to permit the said clamp finger to engage the slug when it is taken by the fingers, and for causing it to disengage the slug after the printing 30 operation.
4. In mechanism as set forth in claim 3, a gripper on the carrier adapted to clamp the slug endwise as it is taken by the fingers, and means for causing said gripper to release the slug after the printing operation.
5. In a machine of the character specified 35 the combination of a feed chute, means for ejecting the slugs therefrom, a rotary carrier adjacent the feed chute adapted to take an ejected slug and carry same past the printing point, a gripper pivoted on the side of the carrier and adapted to clamp and hold the slug endwise on the carrier, and a rotatable cam mounted on said carrier adapted to permit the gripper to engage the slug at the taking point and to cause the gripper to release the slug after the printing operation.
6. In a machine of the character specified; the combination of a feed chute, means for ejecting slugs therefrom, a rotary carrier adjacent the feed chute adapted to take an ejected slug and carry same past the printing point; and means for turning the 50 slug while it is still carried by the carrier so that it will be discharged foot foremost from the carrier.
7. In mechanism as set forth in claim 5, means on the carrier for turning the slug 55 after the printing operation and before it is discharged from the carrier so that the slug will be discharged foot foremost from the carrier.
8. In mechanism as set forth in claim 1, means on the carrier for turning the slug 65 before it is discharged from the carrier so that the slug will be discharged foot foremost from the carrier.
9. In mechanism as set forth in claim 2; means on the carrier for turning the slug 70 after the printing operation and before it is discharged from the carrier, so that the slug will be discharged foot foremost from the carrier.
10. In mechanism as set forth in claim 3; 75 means on the carrier for turning the slug after the printing operation and before it is discharged from the carrier so that the slug will be discharged foot foremost from the carrier.
11. In mechanism as set forth in claim 4; 80 means on the carrier for turning the slug after the printing operation and before it is discharged from the carrier, so that the slug will be discharged foot foremost from the carrier.
12. In mechanism as set forth in claim 12; means on the carrier for turning the slug after the printing operation and before it is discharged from the carrier so that the slug will be discharged foot foremost from the carrier.
13. In mechanism as set forth in claim 1; 90 a finger mounted on the cam shaft adapted to engage the slug and turn it so that it will be discharged foot first from the carrier.
14. In mechanism as set forth in claim 2; 95 a finger mounted on the cam shaft adapted to engage the slug and turn it so that it will be discharged base first from the carrier.
15. In mechanism as set forth in claim 3; 100 a finger mounted on the cam shaft adapted to engage the slug and turn it facewise so that it will be discharged base first type uppermost from the carrier.
16. In a machine of the character specified; the combination of a feed chute, a slide 105 for ejecting slugs therefrom, a carrier adapted to take an ejected slug and carry same past the printing point, means for reciprocating the slide detachably connected therewith; with manually controlled means whereby the reciprocating means may be rendered ineffective to operate the slide, or effective to operate the slide, at the will of 110 the operator without stopping the operation of the carrier.
17. In mechanism as set forth in claim 16; an electrical circuit including a signal and a contact piece, such circuit being closed 115 when the manually controlled means is thrown into position to render the reciprocating means ineffective, and the circuit being open when the manually controlled means permits the effective operation of the 120 slide, substantially as described.
18. In a machine of the character specified; the combination of a feed chute, a 125

- slide for ejecting slugs therefrom, a carrier adapted to take an ejected slug and carry same past the printing point and a reciprocating pitman having a detachable connection with the slide, with manually controlled means whereby the pitman may be disengaged from the slide or reengaged therewith at the will of the operator without stopping the reciprocation of the pitman.
- 10 19. In mechanism as set forth in claim 18; a pitman having a notch in its outer end adapted to engage a pin on the slide, a manually operable device adapted in one position to cause the notched end of the pitman to disengage the pin, and in another position to permit the pitman to remain in engagement with the pin.
- 20 20. In mechanism as set forth in claim 18, a pin on the slide, the pitman having a notched end adapted to engage said pin and a bearing portion adjacent the notch; a manually operable cam lever adjacent the slide adapted in one position to engage the notched end of the pitman and cause it to ride out of engagement with the pin and in another position to permit the pitman to remain in engagement with the slide.
- 25 21. In a machine of the character specified; the combination of a feed chute, a slide for ejecting slugs therefrom, a rotary carrier adapted to take an ejected slug and carry same past the printing point, a pitman having one end pivotally connected with a crank pin on the carrier and having another end detachably connected with the slide, whereby the slide can be reciprocated once for each rotation of the carrier with manually controlled means whereby the pitman may be disengaged from the slide or reengaged therewith at the will of the operator without stopping the operation of the carrier or the reciprocation of the pitman.
- 30 22. In mechanism as set forth in claim 21; a pitman having a notch in its outer end adapted to engage a pin on the slide, a manually operable device adapted in one position to cause the notched end of the pitman to disengage the pin, and in another position to permit the pitman to remain in engagement with the pin.
- 35 23. In mechanism as set forth in claim 21; a pin on the slide, a notched end in the pitman adapted to engage said pin, a slide bearing portion on the pitman adjacent the notch, a manually operable cam lever adjacent the slide adapted in one position to engage the notched end of the pitman and cause it to ride out of engagement with the pin, and in another position to permit the pitman to remain in engagement with the slide.
- 40 24. In mechanism as set forth in claim 18; an electrical circuit including a signal and a contact piece, such circuit being closed when said manually controlled means is thrown into position to disengage the pitman from the slide; and the circuit being open when said manually controlled means permits the pitman to be engaged with the slide.
- 45 25. In mechanism as set forth in claim 20; an electrical circuit including a signal and a contact piece, such circuit being closed when said cam lever is thrown into position to disengage the pitman from the slide, and the circuit being open when the said cam lever is in ineffective position.
- 50 26. In mechanism as set forth in claim 23, an electrical circuit including a signal and a contact piece, such circuit being closed when said cam lever is thrown into position to disengage the pitman from the slide, and the circuit being open when the said cam lever is in ineffective position.
- 55 27. In mechanism of the character specified; the combination of a feed chute, means for ejecting slugs therefrom, and means for taking the ejected slug and presenting same to the printing point; with devices between successive series of slugs adapted to be fed with the slugs through the chute; a trip adjacent the chute adapted to be actuated by the ejection of such a device; and means controlled by said trip whereby when such a device is ejected an indicating mark will be impressed upon the paper simultaneously with the printing thereon by the slug ejected with said device.
- 60 28. In mechanism as set forth in claim 27; an electrical circuit including a circuit closer adapted to be operated by the said trip and a signal, whereby when the trip is actuated by the discharge of a device from the chute a signal is given to the operator.
- 65 29. In mechanism of the character specified; the combination of a feed chute; a slide for ejecting slugs therefrom; a rotary carrier for taking the ejected slug and presenting same to the printing point; a marker on said carrier; and means for normally holding the marker off impression; with cam plates between successive series of slugs adapted to be fed with the slugs through the chute; a trip adjacent the chute adapted to be actuated by the ejection of a cam-plate; and means controlled by said trip whereby the marker is caused to impress the paper simultaneously with the printing thereon by the slug ejected with said cam-plate.
- 70 30. In mechanism as set forth in claim 29; an electrical circuit including a circuit closer adapted to be operated by the actuation of said trip and a signal, whereby when the trip is actuated by the discharge of a cam-plate from the chute a signal is given to the operator.
- 75 31. In mechanism as specified in claim 27; a rotary slug carrier; a marker thereon; a

spring normally holding said marker in retracted position; a trip pin slidably mounted beside the carrier adapted to be projected so as to throw the marker into operative position; and means controlled by the trip for throwing said trip-pin into position to engage the marker when the device is ejected from the feed chute.

32. In mechanism as set forth in claim 29; 10 a trip-pin adapted to be projected in the path of the marker to project the latter into impression position; a lever pivoted beside the slide; operative connections between said lever and said trip pin; and 15 means controlled by the said trip whereby when the latter is actuated by the ejection of a cam-plate the said lever is actuated by the slide and the trip-pin thrown into position to cause the marker to make an impression.

33. In mechanism as set forth in claim 27; 20 a slide for ejecting slugs from the feed chute; a catch on said slide; a lever pivoted beside the slide; a device pivotally connected to the upper end of said lever adapted to be depressed by said strip into position to engage the catch on the lever when the trip is actuated by the ejection of a device from the feed chute; whereby the slide is 25 caused to oscillate the said lever; and means controlled by said lever for causing the impressing of an indicating mark upon the paper.

34. In mechanism as set forth in claim 29; 30 a catch on the slide; a lever pivoted beside the slide; a device pivotally connected to the upper end of said lever; an arm connected with the trip adapted to depress said device into position to engage the catch on 35 the lever when the trip is actuated by the ejection of a cam-plate from the feed chute; whereby the slide is caused to oscillate the said lever; and means controlled by said lever for causing the impressing of an indicating mark upon the paper.

35. In mechanism of the character specified; a rotary slug carrier; a marker thereon; a spring normally holding said marker in retracted position; a trip pin slidably 50 mounted beside the rotary carrier adapted to be projected so as to throw the marker into operative position; means for throwing said trip pin into position to engage the marker; and means for retracting the trip- 55 pin.

36. In combination, a feed chute, a slide for ejecting slugs from the feed chute; a catch on said slide; a lever pivoted beside the slide; a device pivotally connected to the upper end of said lever; a trip adapted 60 to be actuated by the ejection of a controlling plate from the feed chute; an arm connected with said trip adapted to depress said device into position to engage the catch

on the lever when the trip is actuated by the ejection of a controlling plate from the feed chute, whereby the slide is caused to oscillate the said lever; and means controlled by said lever for causing the impressing of an indicating mark upon the paper.

70

37. In mechanism of the character specified; a rotary slug carrier; a marker thereon; a spring normally holding said marker in retracted position; a trip pin slidably mounted beside the rotary carrier adapted to be projected so as to throw the marker into operative position; a feed chute; a slide for ejecting slugs and controlling plates from the feed chute; a catch on said slide; a lever pivoted beside the slide; a device pivotally connected to the upper end of said lever; a trip adapted to be actuated by the ejection of a controlling plate from the feed chute and adapted to depress said device into position to engage the catch on the lever when the trip is actuated by the ejection of a controlling plate; whereby the slide is caused to oscillate the said lever; and means connected with said lever for projecting the trip pin, substantially as described.

90

38. In a machine of the character specified; the combination of a feed chute; means for ejecting slugs therefrom; means adapted to take an ejected slug and carry same past the printing point, an inking roll for supplying ink to the slugs, an ink fountain, and a ductor roller for supplying ink from the fountain to the inking roll; with means whereby each time the feed chute is loaded the ductor is caused to supply ink from the fountain to the ink roll.

95

39. In a machine of the character specified in claim 38; a ductor operating as a distributing roller in the intervals between the feed chute loading operations.

105

40. In a machine of the character specified in claim 38; means for supporting loaded galleys in position to discharge into the feed chute, and means whereby each time a loaded galley is placed upon said supporting means the ductor roller is moved into contact with the fountain.

110

41. In mechanism as set forth in claim 40, means whereby when the galley is removed the ductor roller moves from the fountain and acts as a distributing roller until another galley is placed in position on the support.

115

42. In mechanism of the character specified in claim 38; means whereby when a loaded galley is placed in position on the machine to supply slugs to the chute the ductor roller is brought into contact with the fountain, and when the galley is removed the ductor roller moves into contact with the inking roll and remains in contact therewith and acts as a distributing roll until another galley is placed in position to deliver slugs to the feed chute.

120

125

43. In mechanism of the character specified, the combination of means for feeding slugs, means for presenting the slugs to the printing point, and rollers for inking the slugs before they reach the printing point; a galley support for supporting loaded galleys for loading slugs into the feed chute; an ink fountain, and a ductor roller for supplying ink from the fountain to the inking devices; with devices connected with the ductor roller and with the galley support whereby when a loaded galley is placed upon the galley-support preparatory to introducing slugs into the feed chute the said ductor will be brought into contact with the fountain, and when the galley is removed the said roller will transfer ink to the ink rollers and will act as a distributor until another loaded galley is placed in position preparatory to supplying slugs to the feed chute.
44. In mechanism of the character specified, an ink distributing roll, an ink fountain, and a combined ductor roller and distributor, and means whereby each time the feed chute is charged the ductor roller is brought into contact with the fountain, and when the galley is removed the ductor roller moves into contact with the ink distributing roll and remains in contact therewith until the feed chute is again charged.
45. In combination, an ink distributing roll, an ink fountain, and a combined ductor roller and distributor, and means whereby the ductor roller is brought into contact with the fountain at irregular intervals and normally remains in contact with the distributing roll and acts as a distributing roller, substantially as described.
46. In mechanism as set forth in claim 6, a receiving galley, a chute for directing the discharged slug into such galley, and a yieldingly mounted front plate on said chute to prevent jamming of the slugs in the chute.
47. In mechanism as set forth in claim 6, a receiving galley, a chute for directing the discharged slugs into such galley, said chute having a yieldingly mounted front gate to prevent jamming of the slugs in the chute; and a rotary packer for forwarding the slugs in the receiving galley.
48. In a machine of the character specified; the combination of a feed chute, means for ejecting slugs therefrom, a rotary carrier adjacent the feed chute adapted to take an ejected slug and carry same past the printing point; a clamp on the carrier adapted to clamp said slug flatwise; and means for permitting the said clamp to engage the slug when it is taken by the carrier and causing it to disengage the slug after the printing operation; with means on the carrier for turning the slug before it is discharged from the carrier so that the slug will be discharged foot foremost from the carrier; and means for holding the slug on the carrier while it is being turned.
49. In mechanism as set forth in claim 48; the means for holding the slug on the carrier including grippers adapted to clamp the slug endwise as it is taken by the carrier and hold it while being turned, and means for causing said grippers to release the slug after the printing operation.
50. In a machine of the character specified; the combination of a feed chute, means for ejecting the slugs therefrom, a rotary carrier adjacent the feed chute provided with radially projecting fingers adapted to take an ejected slug and carry same past the printing point; a spring pressed clamping finger pivoted on the carrier and adapted to clamp said slug facewise on the fingers, and means for permitting the said clamp finger to engage the slug when it is taken by the fingers, and for causing it to disengage the slug after the printing operation; with means on the carrier for turning the slug after the printing operation and before it is discharged from the carrier so that the slug will be discharged foot foremost from the carrier; and means for holding the slug on the carrier while it is being turned.
51. In mechanism as set forth in claim 50; the means for holding the slug on the carrier including grippers adapted to clamp the slug endwise as it is taken by the carrier and hold it while being turned, and means for causing said grippers to release the slug after the printing operation.
52. In a machine of the character specified; the combination of a feed chute, means for ejecting slugs therefrom, a rotary carrier adjacent the feed chute adapted to take an ejected slug and carry same past the printing point; a clamp on the carrier adapted to clamp said slug flatwise; and means for permitting the said clamp to engage the slug when it is taken by the carrier and causing it to disengage the slug after the printing operation; with a finger mounted on the cam shaft adapted to engage the slug and turn it so that it will be discharged foot first from the carrier; and means for holding the slug on the carrier while it is being turned.
53. In mechanism as set forth in claim 52; the means for holding the slug on the carrier including grippers adapted to clamp the slug endwise on the carrier, and a rotatable cam mounted in the carrier adapted to permit the grippers to engage the slug at the taking point and to cause the grippers to release the slug after the printing operation.
54. In a machine of the character specified; the combination of a feed chute, means for ejecting the slugs therefrom, a rotary carrier adjacent the feed chute provided with radially projecting fingers adapted to take an ejected slug and carry same past the

printing point; a spring pressed clamping finger pivoted on the carrier and adapted to clamp said slug facewise on the fingers, and means for permitting the said clamp finger to engage the slug when it is taken by the fingers, and for causing it to disengage the slug after the printing operation; a finger mounted on the cam shaft adapted to engage the slug and turn it facewise so that it will be discharged base first type uppermost from the carrier; and means for holding the slug on the carrier while it is being turned.

5

In testimony that I claim the foregoing as my own, I affix my signature.

PAUL F. COX.
